UNITED STATES PATENT OFFICE.

EDGAR A. McALLISTER, OF BALTIMORE, MARYLAND, ASSIGNOR, BY MESNE ASSIGNMENTS, TO THE McALLISTER GAS-LIGHT, HEAT AND POWER COMPANY, OF WEST VIRGINIA.

PROCESS OF CARBURETING.

SPECIFICATION forming part of Letters Patent No. 645,425, dated March 13, 1900.

Application filed August 29, 1899. Serial No. 728,830. (No specimens.)

To all whom it may concern:

Be it known that I, EDGAR A. McALLISTER, a citizen of the United States, residing at Baltimore, in the State of Maryland, have invented certain new and useful Improvements in Processes of Carbureting Aeriform Fluids, of which the following is a specification.

This invention relates to a process for carbureting aeriform fluid.

10 In the accompanying drawing, the apparatus is shown in section, except the compressor, pipes, and regulating-valves.

The letter A designates a gas-engine arranged with a compression-cylinder a to compress the atmospheric air.

15 B is the humidity-eliminator, C the carbureter, and D the gasometer.

From the compressor a a pipe E extends to and projects into the eliminator B. In this 20 pipe E is arranged a safety-valve e to discharge any excess of pressure, a regulating-

valve e' to govern the amount of pressure in the eliminator, and a diffuser e² to spray the air being discharged into the eliminator. 25 From the eliminator extends the pipe F to the carbureter, into which it projects nearly to the bottom. In this pipe F is a regulating-valve f, which governs the amount of pressure carried in the carbureter, and the

30 lower end of the said pipe F is provided with a diffuser c' to spray the air as it enters the hydrocarbon. From the carbureter extends the pipe G to the gasometer, entering the latter at the bottom and projecting above the 35 liquid packing g. In this pipe is arranged a regulating-valve g' to govern the amount of pressure carried in the gasometer. From the gasometer extends the pipe H, which furnishes the supply of gas for consumption

40 and to drive the engine A, the branch pipe h being provided with a governor h' to govern the supply of gas to the engine, said governor being connected by a pipe h² to the pipe E between the regulating-valve e' and compression-cylinder a in order to regulate the working 45 of the engine in accordance with the amount of pressure carried in the eliminator B.

The engine A may be of any construction 50 and actuated by steam or other suitable

means; but in this case I prefer using a gas-engine, as the power therefor can be derived from the product of the apparatus. The compression-cylinder a is of the usual kind provided with a piston and induction and education valves. 55

The humidity-eliminator B in this instance consists of a chamber b, in which the aeriform fluid is compressed, and a chamber b', which contains sulfuric acid b⁷ or any suitable absorbent. Between the two chambers is arranged a cut-off valve b⁶ and a properly-constructed check-valve b² to prevent any back-flow of the fluid. At the bottom of the chamber b is arranged an automatic discharge device consisting of a float b³, lever b⁴, and a valve b⁵, the latter being operated when the water eliminated from the air reaches a given height by the float rising, which through the medium of the lever actuates the discharge- 70 valve.

The carbureter C in this instance consists of a chamber c, which contains the hydrocarbon c². The supply-pipe F extends nearly to the bottom of the carbureter and is provided at 75 its lower end with a diffuser c' to spray the aeriform fluid as it is subjected to the hydrocarbon.

The gasometer D is of the usual form, consisting of a fixed tank d and a movable tank d', with suitable liquid packing g to form a gas-tight joint between the two tanks, the supply-pipe d² and the discharge-pipe d³ connecting with the chamber above the packing g. 80

The safety-valve, check-valve, regulating- 85 valves, and engine-governor are of the usual well-known form. Therefore a detailed description of the same is unnecessary.

In the operation of the apparatus, there being always sufficient gas retained in the gasometer D to start the engine, which is done in the usual manner, the air compressed by the compression-cylinder a passes through the pipe E, regulating-valve e', and diffuser e², where it enters the chamber b of the eliminator B and is confined therein by the cut-off valve b⁶ until from thirty to fifty pounds pressure is accumulated, this amount of pressure being sufficient to eliminate or exclude nearly all the humidity from the aeriform 90 95 100

fluid, the humidity condensing and accumulating at the bottom of the chamber *b*, from which, after a predetermined amount is accumulated, it is discharged by the float rising, 5 which opens the valve *b*⁵ through the intervening lever *b*⁴. As soon as sufficient water has been discharged to lower the float the valve *b*⁵ is closed. Thus the accumulating water is constantly being disposed of automatically. 10 When the desired pressure is accumulated in the chamber *b* and the greater amount of humidity eliminated, the cut-off valve *b*⁶ is gradually opened, which allows the aeriform fluid to pass to the chamber *b* 15 of the eliminator *B*, where it comes in contact with the sulfuric acid, which, having a great affinity for humidity, entirely eliminates any humidity from the aeriform fluid which might remain therein, leaving the 20 same in condition to freely and uniformly absorb the hydrocarbon and bring the molecules of the aeriform fluid and hydrocarbon in actual contact with each other. From the eliminator *B* the fluid passes to the carbureter *C* 25 through the pipe *F* and diffuser *c* at the lower part of the chamber *c* and expands into the hydrocarbon from thirty pounds pressure to five pounds, (the amount carried in the carbureter,) which, being free from humidity, effects a uniform and proper amount of hydro- 30 carbon absorption necessary to produce the desired combustion and economical consumption of the hydrocarbon. From the carbureter *C* the gas passes to the gasometer *D*, 35 where it is again expanded and retained at about two pounds pressure; but as the second expansion takes place where there is no hydrocarbon to be absorbed the molecular parts, although occupying a larger space, contain the same amount of hydrocarbon as 40 absorbed in the carbureter. From the gasometer the gas passes to the distributing-pipes ready for consumption.

In case the compressor is supplying the aeriform fluid faster than the consumption of the gas the increase of pressure in the pipe 45

E acts on the governor *h*' and regulates the supply of gas to just keep the engine *A* running. If under this condition the pressure still increases, the surplus over the predetermined amount carried is discharged by the safety-valve *e*. 50

By this apparatus a uniform and economical gas is produced and maintained which will not condense or the component parts 55 thereof separate. The relative proportion of the parts can be accurately regulated to produce gases containing from the minimum to the maximum amount of hydrocarbon, as desired, and the apparatus being practically 60 self-actuating it requires only the minimum of labor to operate the same, thereby procuring economy both in attendance and consumption of hydrocarbon, the latter being due to the proper proportion of the component parts of the gas, due to the perfect regulation of the apparatus and the process and method therein employed. 65

Either of the elements disclosed may be varied—that is, by dispensing with, adding 70 to, or changing the form of the parts thereof.

A gasometer is shown and claimed in some of the combinations. It may, however, be dispensed with and the pipe *H* act as an equivalent. Therefore such pipe is included 75 as the equivalent of the gasometer.

The apparatus for carrying out this process I reserve for another patent, the application for which was filed August 29, 1899, Serial No. 728,828. 80

I claim—

The process of carbureting aeriform fluid consisting in compressing and cooling the fluid to eliminate the humidity and then subjecting the compressed and cooled fluid to 85 hydrocarbon while it is expanding.

In testimony whereof I affix my signature in the presence of two witnesses.

EDGAR A. MCALLISTER.
